Attorneys

UNITED STATES PATENT OFFICE.

ARTHUR E. CUSTER, OF LOS ANGELES, CALIFORNIA.

CARPET, RUG, AND FLOOR BRUSH.

Application filed July 31, 1924. Serial No. 729,254.

This invention relates to brushes and in particular to brushes adapted to be attached to vacuum cleaners for cleaning and washing rugs.

5 It is an object of the invention to provide a brush attachable to a vacuum cleaner with a support facilitating the movement of the brush over the rug.

10 It is a further object of the invention to provide a brush having a support extending through the bristles of the brush and which will be adjustable so that the brush may be adjusted relatively to the surface which is being cleaned.

15 With the foregoing and other objects in view which will be more specifically pointed out in the following detailed description and defined in the appended claim, reference is had to the accompanying drawings for an 20 illustrative embodiment of the invention, wherein—

Fig. 1, is a partial perspective showing the improved brush mounted upon a vacuum forming device.

25 Fig. 2, is a front elevation of the brush shown in Fig. 1, parts being broken away and shown in section.

Fig. 3, is a bottom plan view of the brush as shown in Fig. 2.

30 Figures 4, 5, and 6 are top plan, side elevation, and bottom plan views of a modified form of the invention.

Fig. 7, is a view illustrating the utility of the improved brush as shown in Figures 1 35 to 3 inclusive, when cleaning a carpet or rug.

Referring to the accompanying drawings wherein similar reference characters refer to similar parts, the brush consists of a body 40 10 having an aperture 11 therein which is adapted to register with the opening of a fitting 12 attached to the suction pipe 13 of a vacuum forming means, such as that of the ordinary vacuum cleaner. Bristles B are 45 arranged upon the underside of the body 10 around the edge thereof, so as to leave a central vacant or bare space 14; upon the opposite ends of the body 10 are mounted suitable supports generally designated by 50 the reference character 15.

The supports 15, consist of a threaded shank 16 having a wing nut or similar twisting device 17 secured upon its upper end and provided with a suitable socket 18 adapt-

ed to receive a ball 19 which bears against 55 suitable smaller balls 20 disposed within the socket. The ball 19 forms an anti-friction device for the support 15 and as shown, projects from between the bristles of the brush and bears upon the floor F. As a 60 means for adjusting the brush, the threaded shank extends through a threaded collar 21 secured upon the body 10 by means of screws 22, so that as the shank 16 is rotated it will be forced upwardly or downwardly through 65 the body 10. A suitable lock nut 23 is adapted to retain the shank 16 in adjusted position.

In this manner it is seen that a brush is provided which has an adjustable support 70 so that the bristles of the brush may be raised or lowered relatively to the floor, thereby prolonging the life of the brush.

In Figures 4, 5 and 6, the adjustable support is shown as being mounted upon a brush of ordinary construction. With reference, in particular, to Fig. 7, it is seen that when a vacuum brush having the adjustable supports 15 mounted thereon is moved over a carpet C, the carpet beneath the supports 15 is held in contact with the floor F. As clearly shown in Fig. 7, the carpet C between the supports 15 may be lifted by suction of the vacuum forming means off of the floor 85 so that air will be drawn directly through the carpet, thereby increasing the cleaning efficiency of the brush.

It is to be understood that various changes may be made in the details of construction without departing from the spirit or scope 90 of the invention as defined by the appended claim.

What I claim is:

A caster comprising a member adapted to be mounted upon the article to be supported, 95 a shank threadedly extending through said member, a handle rigid with one end of the shank by which the shank may be vertically adjusted with respect to said member, a socket provided on the other end of the 100 shank, a ball retained in said socket and rotatable therein, and a lock nut threaded onto said shank adapted to be tightened against said member for locking said shank against rotation relatively to said member. 105

In testimony whereof I have signed my name to this specification.

A. E. CUSTER.
